UNITED STATES PATENT OFFICE.

BERT L. HERRICK, OF OAKLAND, CALIFORNIA.

BAG OR NET FASTENER.

Application filed May 22, 1922. Serial No. 562,672.

To all whom it may concern:

Be it known that I, BERT L. HERRICK, a citizen of the United States, residing in the city of Oakland, county of Alameda, and 5 State of California, have invented a new and useful Bag or Net Fastener, of which the following is a specification.

This invention relates to devices for fastening around the neck of a bag to hold the 10 same closed, and is intended more particularly for laundry bag closures.

In laundries, it is customary to inclose certain classes of individual wash in separate bags made of fabric or netting, and close 15 the same for general handling, before, during and after the washing process or operation. When ready for the wash, a number of these bags are thrown into a washing machine and subjected to the washing operation. The present closure devices for the 20 bags and with which I am familiar, now and then open during the tumbling washing process, and cause annoyance, trouble and confusion, resulting in loss of time and involving 25 more or less serious difficulty in identifying the individual belongings, and which very frequently necessitates that the remaining unidentified pieces must be taken to all the customers who are assigned the 30 unfortunate bags, for individual identification and claim.

The prime object of my invention is to overcome the above deficiencies by rendering the fastening secure against the accidental 35 opening of the bag.

A further object is to render the securing means easy to open, when its opening is desired. And a still further object is to so construct the device that it will present 40 smooth inner and outer surfaces, to eliminate all possible chances of the threads or cords of the bag or net from catching on any edge or corner.

With the above and other objects in view, 45 my invention consists in certain novel features of construction, form and arrangement of parts. The accompanying sheet of drawings forming a part of this specification illustrates an embodiment of my invention, 50 and what I claim as new is particularly pointed out in the appended claims following the specification.

In the drawings:

Figure 1 is a perspective view of the bag 55 fastener when open. Figure 2 is a plan of it as it appears when closed. Figure 3 is a

view of the device in the hand of an operator compressing the same, showing the position the link assumes when so compressed.

In the figures:—A piece of metal, prefer- 60 ably a flat strip of spring brass or copper as 1, is bent back as at 2, to bring the two ends into proximity when closed.

The sides of the body of the device, are formed by preference, with flat curvatures 65 as shown in Figure 2, to enhance its resiliency. One of the ends as 3, is turned inward and formed into an inturned hook 4, whose extremity is chamfered to present a sharp edge 5, for a purpose to be presently de- 70 scribed. The other end of the body 1 is formed into an eye 6, in which is hinged a wire link 7, adapted to engage the hook 4 and so hold the two ends of the body together. To prevent the accidental disen- 75 gagement of link 7 from hook 4, I provide a tongue 8 of resilient material, and preferably secure it to the body 1 by soldering, as that insures a smooth surface. The said tongue has its free end overlapping the 80 hook 4 and is there recurved as at 9, so that when the two side members of body 1 are pressed together as indicated in Figure 3, the link 7 will not become disengaged from the hook 4, but will be directed away from 85 the end of the hook by the said recurved end, as also indicated in Figure 3, and will snap back into the hook when released. In order to disengage the link 7 from hook 4 to open 90 the lock, the body must be compressed as shown in Figure 3, and the operator must then with his other hand, push the link back and over the beveled edge 5, thereby releasing the jaws from engagement with 95 each other.

The tongue 8 normally bears and rests upon the sharp chamfered edge 5 of the hook 4, and is only displaced therefrom by the link, but the link cannot pass this edge be- 100 cause of the recurved end 9 of the tongue. Thus the fastener can only be opened by the positive action of the operator.

I preferably make the body member of my fastener carrying the link, a little shorter in length than the other member, so that 105 the axis of the eye of the former member shall be positioned inward a little to that of the axis of the inturned hook, for a fur- ther precaution measure, so that the link, when the body is compressed will normally 110 move away from the end of the hook.

In use, the mouth of a bag is gathered and

the fastener slipped around its neck, and link 7 seated within the hook 4, thus closing and locking the bag. As all surfaces of the fastener are perfectly smooth, the engagement 5 thereof with the bag is easily accomplished, and the same is true of the reverse operation of disengaging the device from the neck of the bag, when it is desired to open the latter.

I claim:

- 10 1. A bag fastener, comprising two body members adapted to approach and recede from each other, one of said members having an inturned end and an inturned hook at the extremity of said end, and a tongue adapted 15 to contact the said hook, and the other of said body members having a link hinged thereto at its extremity and adapted to engage the said hook, the said tongue preventing disengagement of said link when the 20 fastener is closed.
2. A bag fastener, comprising two body members adapted to approach and recede from each other, one of said members having an inturned end and an inturned hook at the 25 extremity of said end, and a tongue having a recurved end adapted to contact said hook, the latter having a chamfered edge where it contacts the said tongue, and the other body member having a link hinged thereto, 30 and adapted to engage the said hook and said recurved end of said tongue.
3. A bag fastener, comprising two body members adapted to approach and recede from each other, one of said members having

an inturned end and an inturned hook at the 35 extremity of said end, and a tongue adapted to contact said hook, and the other body member having an outward turned end forming an eye thereon, and a link hinged in said eye, the said link adapted to engage 40 the said hook on said first named member, the said tongue preventing disengagement of said link when the fastener is closed.

4. A bag fastener, comprising, a resilient metallic strip bent back toward itself forming jaws thereby, a tongue secured to one jaw and a link to the other; the said jaws formed with flat curvatures and with their crowns extending outwardly, one of said jaws provided with an inturned hooked extremity engaging the said tongue and adapted 50 to be engaged by the link on the other jaw, the tongue preventing the link from accidental disengagement when the fastener is in service.

5. A bag fastener, comprising two body members adapted to approach and recede from each other, one of said members having an inturned end and an inturned hook at the extremity of said end, and the other 60 body member having a link hinged thereto and adapted to engage the said hook, the latter body member being shorter in length than the former body member, for directing the link away from the end of said hook 65 when engaged therewith, and when the said body members are compressed.

BERT L. HERRICK.
